UNITED STATES PATENT OFFICE.

GEORGE FRANKLIN SUMMERS, OF PLEASANTON, KANSAS.

SEWING-AWL.

SPECIFICATION forming part of Letters Patent No. 608,926, dated August 9, 1898.

Application filed October 7, 1897. Serial No. 654,452. (No model.)

To all whom it may concern:

Be it known that I, GEORGE FRANKLIN SUMMERS, a citizen of the United States, residing at Pleasanton, in the county of Linn and State 5 of Kansas, have invented a new and useful Awl, of which the following is a specification.

My invention is an improvement in sewing-awls for use by leather-workers in general repair-work, such as sewing shoes, harness, and analogous work; and the object 10 that I have in view is to provide an improved awl in which the supply of thread or string (either waxed or unwaxed) and the tension device for said thread are contained or housed 15 wholly within the handle of the implement.

A further object of the invention is to improve the implement with a view to protecting the thread or string in its passage through the work, while insuring the proper tension 20 on the thread; and a further object that I have in view is to provide for the use of eye-pointed awls or needles of different lengths, according to the thickness of the leather or 25 to the nature of the work to be performed.

With these ends in view the invention consists in the novel construction and combination of parts, which will be hereinafter fully described and claimed.

To enable others to understand the invention, I have illustrated the preferred embodiment thereof in the accompanying drawings, forming a part of this specification, and in which—

Figure 1 is a perspective view of my improved awl. Fig. 2 is a longitudinal sectional view through the implement. Fig. 3 is a transverse section on the plane indicated by the dotted line 3 3 of Fig. 2. Fig. 4 is a view illustrating the use of the implement in 40 forming a lock-stitch in the thread. Fig. 5 is a sectional elevation illustrating another embodiment of my invention by which the awl or needle is adjustably and securely fastened to the end of the needle.

Like numerals of reference denote like parts in all the figures of the drawings.

1 designates my improved sewing-awl in its entirety.

Briefly stated, the implement consists of a 50 handle 2, the awl or needle 3, a socketed end piece 4, a plug or closure 5 for the open cham-

bered end of the handle 2, a spindle 6, and a bobbin 7.

The handle 2 of the implement is constructed, preferably, of wood shaped to the form 55 shown by the drawings to provide a contracted front end and an enlarged part. In this enlarged part of the handle is formed a chamber 8 for the accommodation of the spindle 6 and bobbin 7, and said chamber opens through the 60 enlarged part of the handle to receive the plug or closure 5. This plug or closure is constructed to fit tightly in the open rear end of the chamber, and it may be held in position either by frictional contact with the handle 2 65 or by engaging screw-threads on said handle and the plug or closure. The chamber 8 does not extend through the contracted front end of the handle, and in the solid wall closing the front end of the chamber is fastened one 70 end of the spindle 6. This spindle occupies a central position within the chambered handle, and the rear end of the spindle is fitted in a socket 9, provided centrally in the plug or closure 5, thus supporting both ends of the 75 spindle in place. On the spindle 6 is loosely mounted the bobbin 7, adapted to contain the thread or cord to be used in the formation of the stitches in sewing the leather. This bobbin is free to rotate on the spindle as well 80 as to slide thereon in the act of removing the bobbin or replacing it within the implement. The bobbin may be of any suitable construction; but I prefer to employ a bobbin in which the sleeve or hub is joined to the heads, as 85 shown by Fig. 2.

A tension-spring 10 is fitted within the chambered handle of the implement. This spring is preferably a coil-spring, fitted loosely on the spindle 7, and one end of said spring 90 bears against the wall closing the front end of the chamber 8, while the other end of the spring is seated against one head of the bobbin 7. The tension of the spring normally forces the bobbin lengthwise on the spindle 95 against the head or closure 5 of the implement-handle, and thus the bobbin is confined between the tension-spring and the plug or closure. The heads of the bobbin engage with the plug or closure and with the spring with sufficient frictional contact to restrain the bobbin normally against free rotation on the spindle 100.

6, whereby the thread is placed under the desired tension and is prevented from pulling freely out of the chambered handle of the implement.

5 I attach importance to the peculiar arrangement of the bobbin and its tension-spring within the chambered handle 2 of the implement, because the bobbin and its tension device are housed entirely within the implement-handle and the parts are out of the way of the operator's hand in grasping and manipulating the implement.

The socketed end piece 4 is of cylindrical form and of a diameter corresponding substantially to the diameter of the handle at its contracted front end, and said socketed end piece is fastened firmly or rigidly in said contracted end of the implement-handle. The end piece 3 is provided with an axial bore or passage 11, a radially-threaded aperture 12, and a diagonal guide-eye 13. The radially-threaded aperture 12 opens into the longitudinal bore of the end piece, and in said radial aperture is fitted the threaded shank 25 of a binding-screw 14. The shaft of the awl or needle 3 is thrust or inserted into the longitudinal bore of the end piece, and it is held rigidly in place therein by the clamping action of the screw 14. At the same time 30 the awl or needle 3 may be adjusted longitudinally within the end piece 4 by releasing the clamping-screw 14, adjusting the awl or needle to the required position, and afterward tightening the screw 14 to hold the awl or 35 needly firmly in place. The guide-eye of the end piece is formed therein near the outer extremity and in a position diagonal to the longitudinal bore or passage of said end piece. One end of this guide-eye opens 40 through the cylindrical surface of the end piece, while its other end opens into the longitudinal bore or passage therein, and said eye is contracted, as at 13, to prevent the thread from being thrust through the extremity of 45 the end piece 4. As shown in the drawings the awl or needle 3 consists of a straight shank pointed at one end, as at 15, provided with an eye 16 near its pointed extremity and with a longitudinal groove or channel 17, 50 which extends from the eye 16 nearly to the heel or butt-end of the awl or needle.

The awl or needle is adjusted in the socketed end piece 4 to have its groove or channel 17 in alinement with the diagonal guide-eye 13 in said socketed end piece, and in this position of the parts the groove or channel of the awl or needle is out of alinement with the radial aperture 12 of the end piece, thus enabling the clamping-screw 14 to bear upon 60 a solid part of the awl or needle.

The handle 2 of the implement is provided with a transverse guide-aperture 18, arranged in the same plane as the diagonal guide-eye 13 of the end piece, whereby the thread may 65 be carried in a straight line from the chambered part of the handle to the guide-eye of the end piece, to the channeled side of the

awl or needle, and through the eye at the pointed extremity of said needle. The closure or plug 5 is now fitted in the open chambered end of the handle in position to receive the free end of the spindle 6 and to bear against one head of the bobbin 7, thus placing the bobbin under tension between the spring and the plug or closure. The implement may be used in any desired manner similar to ordinary tools of this class; but it is especially adapted for service in forming lock-stitches in the work analogous to stitches made by lock-stitch sewing-machines. To 80 use the implement for this purpose, the thread is led out through the guide-aperture in the handle, through the diagonal guide in the socketed end piece, and thence through the eye near one end of the awl or needle, the 85 thread along the handle being adapted to be held between the tool-handle and the thumb of the operator. The awl or needle is forced through the leather, carrying the thread with it, and the awl is then withdrawn, leaving a loop in the thread at the side of the 90 needle. The needle 20 is now passed through this looped part of the thread, thus passing the thread attached to the needle through the looped thread connected with the awl-shaft, and by withdrawing the awl from the 95 hole last made and by pulling on both threads a stitch will be formed similar to the lock-stitch formed by an ordinary sewing-machine. The operation may be repeated as often as required to produce the desired number of 100 stitches proper to unite the parts of the work together.

In case a straight awl or needle is used it may be clamped in the socketed end piece to project the required distance beyond the handle of the implement, and such needle may be extended or retracted, as may be desired, according to the thickness of the work, thus making the device applicable to work of different thicknesses.

Other eye-pointed awls or needles of different lengths and of either straight or curved forms may be used according to the nature of the work, and in either case the needle or awl is held rigidly in the socketed end piece 125 by the action of the clamping-screw.

I do not desire to strictly confine myself to the precise construction of the end piece having a smooth socket, the diagonal eye, and a clamping-screw for rigidly and detachably holding the heel of the awl or needle in said socket-piece, because I am aware that other devices may be substituted for the described construction. In Fig. 5 of the drawings I

have illustrated a simpler device by which the heel of the awl or needle may be rigidly attached to the end piece. In this construction I dispense with the diagonal guide-eye and the binding-screw. In lieu of these parts I construct the end piece with an axial internally-threaded socket 25, which opens centrally through the front end of said end piece. In connection with the threaded socket of the end piece I employ an awl or needle having its heel externally threaded for a suitable distance, as indicated at 26, and said threaded heel is designed to be screwed into the threaded socket for the purpose of rigidly and adjustably fastening the awl or needle to the handle. The described adjustable connection between the awl or needle and the end piece provides a joint which may be used advantageously in other arts—such, for example, as sewing-machines.

I am aware that changes in the form and proportion of parts and in the details of construction may be resorted to without departing from the spirit or sacrificing any of the advantages of the invention.

Having thus described the invention, what is claimed as new, and desired to be secured by Letters Patent, is—

1. A sewing-awl comprising a tapered handle provided with a chamber and with a transverse thread-passage, a closure-plug fitted to the enlarged butt-end of the handle to close

the open rear end of the chamber therein, an end piece fixed to the reduced end of said handle and provided with an axial needle-socket, an eye-formed needle fixed in said needle-socket on the end piece and having a longitudinal groove arranged in the plane of the thread-passage lengthwise of the awl, a fixed spindle within the chambered handle, a bobbin loosely mounted on the spindle, and a pressure-spring housed in the chambered handle and bearing against the bobbin, substantially as described. 35

2. A sewing-awl comprising a chambered handle having a transverse thread-passage, an end piece secured to one extremity of the handle and provided with a needle-socket, and a diagonal thread-passage which opens into the needle-socket and through the end piece to lie in the plane of the thread-passage in the handle, an eye-formed needle secured in the socket of the end piece and having a longitudinal groove which alines with the diagonal passage of said end piece, and a bobbin mounted in the chamber of the handle, 50 substantially as described.

In testimony that I claim the foregoing as my own I have hereto affixed my signature in the presence of two witnesses.

GEORGE FRANKLIN SUMMERS.
